UNITED STATES PATENT OFFICE.

CHARLES A. CONGER, OF OAKLAND, CALIFORNIA.

DESIGN FOR A ROPE-FASTENER.

SPECIFICATION forming part of Design No. 32,194, dated February 6, 1900.

Application filed December 23, 1899. Serial No. 741,475. Term of patent 7 years.

To all whom it may concern:

Be it known that I, CHARLES A. CONGER, a citizen of the United States, residing in the city of Oakland, county of Alameda, State of California, have invented and produced a new and original Design for Rope-Fasteners, of which the following is a specification, reference being had to the accompanying sheet of drawing, forming a part thereof.

As shown in the drawing, the leading or material features of my design consist of the body portion A, having the ring-like ends A', arranged or standing at an inclination to the body portion A, and the upturned hook A², springing from one side of the body A, inter-

mediate the ring-like ends A', said hook extending across the body portion A.

Having thus described my invention, what I claim as new, and desire to secure by Letters Patent, is--

The design for a rope-fastener, as herein shown and described.

In testimony whereof I affix my signature, in the presence of witnesses, this 19th day of December, 1899.

CHARLES A. CONGER.

In presence of—

N. A. ACKER,
JAMES C. MACINNES.
